US0D1026037S

(12) **United States Design Patent** (10) **Patent No.:** **US D1,026,037 S**
(45) **Date of Patent:** **** May 7, 2024**

(54) **STRUCTURAL COOLANT TANK**

(71) Applicant: **Deere & Company**, Moline, IL (US)

(72) Inventors: **Jesse J. Bender**, Waterloo, IA (US);
Noah F. Homan, Waterloo, IA (US);
Jade E. Bender, Waterloo, IA (US)

(73) Assignee: **Deere & Company**, Moline, IL (US)

(**) Term: **15 Years**

(21) Appl. No.: **29/858,038**

(22) Filed: **Oct. 27, 2022**

(57) **CLAIM**

The ornamental design for a structural coolant tank, as shown and described.

DESCRIPTION

FIG. 1 is a rear-top perspective view of a new design for a structural coolant tank;

FIG. 2 is a front-side perspective view of the new design for the structural coolant tank;

FIG. 3 is a rear view of the new design for the structural coolant tank;

FIG. 4 is a front view of the new design for the structural coolant tank;

FIG. 5 is a right side view of the new design for the structural coolant tank;

FIG. 6 is a left side view of the new design for the structural coolant tank;

FIG. 7 is a top view of the new design for the structural coolant tank; and,

FIG. 8 is a bottom view of the new design for the structural coolant tank.

The broken lines in the views depict environmental subject matter only and form no part of the claimed design.

1 Claim, 8 Drawing Sheets
